(57) **CLAIM**

The ornamental design for an expandable medical device as shown and described.

DESCRIPTION

FIG. 1 is a front perspective view of an expandable medical device in accordance with a new design;

FIG. 2 is a rear perspective view of the expandable medical device of FIG. 1;

FIG. 3 is a top plan view of the expandable medical device of FIG. 1;

FIG. 4 is a bottom plan view of the expandable medical device of FIG. 1;

FIG. 5 is a first side view of the expandable medical device of FIG. 1;

FIG. 6 is an opposite side view of the expandable medical device of FIG. 1;

FIG. 7 is a front end plan view of the expandable medical device of FIG. 1; and,

FIG. 8 is a rear end plan view of the expandable medical device of FIG. 1.

The broken lines shown in the figures depict portions of the expandable medical device that form no part of the claimed design.
